UNITED STATES PATENT OFFICE

EDWIN S. MIX, OF ROCHESTER, NEW YORK, ASSIGNOR TO HICKOK MANUFACTURING COMPANY, INC., OF ROCHESTER, NEW YORK, A CORPORATION OF NEW YORK

GARTER

Application filed May 6, 1929. Serial No. 360,643.

The present invention relates to garters and an object of the invention is to provide a garter having an elastic strap portion which is adjustable to legs of different sizes, and 5 does away with the detachable hook connection between one end of the strap and the pad. Another object of the invention is to provide a novel means of adjustably connecting one end of the strap to the pad. Still another object of the invention is to provide a 10 garter having the metal parts reduced to a minimum.

To these and other ends, the invention consists of certain parts and combinations of 15 parts all of which will be hereinafter described: the novel features being pointed out in the appended claims.

In the drawings:

Fig. 1 is a side view of the garter; 20 Fig. 2 is an enlarged section on the line 2—2, Fig. 1;

Fig. 3 is a perspective view of a guide eyelet or grommet;

Fig. 4 is a detailed view of a modification 25 of the invention.

In the embodiment shown in Figs. 1 to 3, there is employed a pad 1 formed of two layers of fabric or leather 2 and stitched together at 3 and having a garment clasp 4 depending 30 therefrom of any suitable construction.

The pad is provided with two guides 5 arranged to converge toward the top of the pad, each guide, in this instance, being formed by providing a slot in the pad and reinforcing 35 the wall of the slot. The reinforcing means consists, in this instance, of an elongated eyelet 6 which is turned over the opposite faces of the pad about the slot and is preferably formed of a non-oxidizable material 40 such as celluloid or bakelite.

The leg band or strap 7, in this instance, is formed of elastic material and has loops 8 and 9 at opposite ends passed through the two eyelets of the pad. The loop 8 is stitched 45 at 10 and is not adjustable, but the inner layer of the loop 9 is secured to a slide 11 which is adjustable on the strap so as to adapt the garter to legs of different sizes.

In order to prevent the looped strap ends 50 slipping in the eyelets and to keep the strap

in a spreaded condition, each eyelet may have a slip preventing means on the side wall engaged by the strap. This means, in this instance, comprises alternate projections 12 and recesses 13 which distort the strap and hold it 55 spreaded.

In the embodiment shown in Fig. 4, the parts are the same except one end of the band or strap which is stitched at 8^a between the layers, so that the two ends of the strap 60 diverge outwardly and upwardly from the pad.

In all embodiments of the invention, the hooked connection between the pad and the strap is eliminated while an adjustable strap 65 for fitting legs of different sizes is obtained. The ends of the strap connect with the pad so they diverge upwardly and outwardly from the pad. The guides are at right angles to the strap and when two guides are provided 70 they converge toward the top of the pad. In the two forms of the invention, a loop at one or both ends of the pad passes through a slot in the pad, the walls of the slot being reinforced by an eyelet made of non-oxidizing 75 material. In all embodiments the guide has means for holding a looped end on the strap in a spreaded condition to prevent it bunching on the guide.

What I claim as my invention and desire to 80 secure by Letters Patent is:

1. A garter comprising a pad formed of substantially pliable material and having a slot therethrough, an elongated eyelet fitted in said slot, a garment clasp carried by the 85 pad, and a strap secured at one end to the pad and having its other end provided with a loop passed through the eyelet.

2. A garter comprising a pad formed of substantially pliable material and having a slot formed therethrough, reinforcing means for the pad at the slot formed of substantially rigid and non-oxidizable material, and a strap secured at one end to the pad and having its other end provided with a loop 95 passed through the slot in the pad, and a garment clasp carried by the pad.

EDWIN S. MIX.
